UNITED STATES PATENT OFFICE.

GEORGE WHITEFIELD ELLIS, OF LYNN, ASSIGNOR TO PERLEY GREEN, OF STONEHAM, MASSACHUSETTS.

SOLE FOR BOOTS OR SHOES.

SPECIFICATION forming part of Letters Patent No. 377,244, dated January 31, 1888.

Application filed October 26, 1887. Serial No. 253,460. (No model.)

To all whom it may concern:

Be it known that I, GEORGE WHITEFIELD ELLIS, a citizen of the United States, residing at Lynn, in the county of Essex and State of Massachusetts, have invented certain new and useful Improvements in Soles for Boots or Shoes, of which the following is a specification.

This invention relates to boot or shoe soles of that class in which small pieces or scraps of leather are utilized; and its object is to provide a composite sole possessing advantages in point of inexpensiveness in manufacture, durability, and neatness, and one which will be equally as serviceable as those made of a solid piece of leather.

In the drawings, Figure 1 is a plan view of a sole embodying my invention. Fig. 2 is a transverse section thereof. Fig. 3 is a longitudinal section. Fig. 4 is a detail section illustrating one of the staples. Fig. 5 is a detail perspective view of the pieces separated. Fig. 6 is a plan view of a modification.

Corresponding parts in the figures are denoted by the same letters of reference.

Heretofore in the manufacture of soles of this class two marginal pieces of leather have been employed, having beveled overlapping front ends, and forming a central space designed to be filled in with one or more scraps of leather, all the sections being then secured together by cementing or gluing binding-sheets upon one or both sides of the sole. To manufacture this form of sole, it is necessary to employ workmen to scarf or bevel the ends, as described, as also for the purpose of cutting out and pasting the binding-sheets upon them, thus involving considerable expense and labor.

My invention is designed to obviate these disadvantages; and to this end I employ two sections of leather, A A', which, when their inner edges are placed together, correspond in horizontal plan or section to the shape of the outer sole, B. The section A has a portion of its inner front end cut away, as shown at a, and a projecting piece, a', is provided upon the inner front edge of the section A', corresponding in shape to and designed to occupy the recess a in the section A when the sections are secured together. By thus forming an angle in the line of the joint at the front edge a neat finish is secured.

In securing the sections A A' together the inner adjoining edges are first supplied with glue, cement, or other securing substance, and are then secured by means of staples a", which hold the sections while the glue is setting. The sole thus formed is then glued or secured in any suitable manner to the outer sole.

In the modification shown in Fig. 5 four sections are used, the front sections, A" A", being similar to the front portion of the sections A A' in the hereinbefore-described construction. These sections A" A" are cut away at their rear edges, forming, when said sections are in position, a cone-shaped recess, occupied by the forward portions of two similarly-shaped trapeziform sections, C C'. All of the sections are then secured together, as before described. In this construction smaller pieces of leather can be utilized.

It will be noted that by my invention a center piece or filling is entirely dispensed with, and that all the pieces forming the composite top sole will be securely retained in position in the construction of the shoe by sewing or nailing. Thus, when the bottom sole, B, is removed in repairing the shoe, the parts or pieces of the top sole will remain in position and not fall out or become displaced, as is the case with the center piece in previous constructions or forms of composite soles.

The advantages of my invention will be readily understood from the foregoing description, taken in connection with the annexed drawings. It is obvious that by providing the angle at the toe the necessity of securing binding-sheets on either or both sides, as also the practice of scarfing or beveling and overlapping the inner front ends, is entirely obviated, and, furthermore, a much neater finished sole is thereby secured.

While I prefer to employ staples to secure the sections together while the glue is setting, it will be manifest that they may be dispensed with and the glue alone employed to retain the sections together.

I claim as my invention—

1. As an improved article of manufacture, a sectional sole for boots or shoes, comprising two sections, one of which has a recess near its front inner end, the other section being formed with a projecting portion near its end corre-

sponding in shape to and adapted to fill said recess, and staples for securing the sections together, substantially as set forth.

2. A composite sole composed of two or more pieces secured together at their adjoining edges and having all the pieces extending to the outer edge of the sole, whereby a central filling is obviated and all the pieces will be retained in position by sewing or nailing in the construction of the shoe, said pieces forming two united sections, one of which has a recess near its front inner end, while the other section is formed with a projecting portion near its end corresponding in shape to and adapted to fill said recess, substantially as set forth.

3. The herein-described sectional sole for boots or shoe, comprising two sections, one of which has a recess near its front inner end, the other section being formed with a projecting portion near its end corresponding in shape to and adapted to fill said recess, substantially as set forth. 20

In testimony whereof I affix my signature in presence of two witnesses.

GEORGE WHITEFIELD ELLIS.
